UNITED STATES PATENT OFFICE.

FREDERICK S. McCULLOUGH, OF WILKINSBURG, PENNSYLVANIA.

THERMIONIC TUBE.

Application filed May 6, 1925. Serial No. 28,341.

To all whom it may concern:

Be it known that I, FREDERICK S. McCULLOUGH, a citizen of the United States, residing at Wilkinsburg, in the county of Allegheny and State of Pennsylvania, have invented certain new and useful Improvements in Thermionic Tubes, of which the following is a specification.

This invention is for an improvement in thermionic tubes or hot cathode devices.

The present invention has for its object to provide, in a cathode device of this kind, a cathode which may be heated by alternating or pulsating currents, so that ordinary house lighting current may be employed in the operation of the tubes. This cathode is so constructed as to produce no perceptible hum or noise or current variation in the circuit in which it is employed, due to the fluctuating field set up by such alternating current, provided, of course, that the voltage of such alternating or pulsating current is properly maintained with respect to the construction of the tube.

The invention may be readily understood by reference to the accompanying drawings, in which:

Fig. 1 is a diagrammatic sectional view of a tube and a simple circuit embodying same;

Fig. 2 is a similar view of a slightly different circuit;

Fig. 3 is a detail view, showing on a larger scale the construction of the cathode.

In the drawings, I have illustrated conventionally a three electrode type of tube, but the invention is not restricted to any particular tube construction or type of tube.

In the drawings, 5 designates a suitable envelope containing a plate or anode 6. Inside the anode, as usually arranged, is a grid or control electrode 7. Inside the grid and out of contact therewith is the cathode.

The cathode construction includes a body or rod 8 of porcelain or other suitable material in which is enclosed a resistance heater 9 having lead wires 10 extending out of the top of the tube, these wires being connected in an alternating current circuit, which may include a step-down transformer 11 to maintain the voltage at a proper value for the construction of the tube.

Surrounding the rod, and preferably tightly fitted thereto, is an inner sleeve 12 of a magnetic nature, such as nickel or copper. On the outside of this sleeve is a thin

coating of heat resistant enamel or insulation 13, and fitted over this is an outer sleeve 14 which is the actual cathode and which preferably has a coating of a high emission character.

The heater wires are preferably co-extensive with the porcelain rod, and the inner sleeve 12 is preferably slightly longer than the cathode 14 and extends above and below the cathode.

In operation, the tube may be connected in any standard or preferred circuit, and the magnetic shield 12 may be grounded through lead wire 12a. The heater is energized, and this in turn heats the porcelain rod and the rod acts as a heat reservoir so that the temperature of the cathode will not fluctuate with the maximum and minimum current values in the alternating heating circuit. The heat from the rod will be conducted through the inner sleeve 12 to the outer sleeve or cathode 14, raising it to an efficient emitting temperature.

Provided that the voltage in the heater is properly proportioned, to the construction of the tube, the magnetic shield 12 will prevent the oscillating field produced by the alternating heater current from affecting in any manner the operation of the tube, so that no hum or alternating current fluctuation is apparent in the tube circuit. The grounded shield eliminates any generation of eddy currents in the cathode, and neutralizes the capacity between the heater wires and the cathode.

Instead of grounding the magnetic shield, it may be desirable to connect the cathode and the shield through a potentiometer P, as shown in Fig. 2.

From the foregoing, it will be evident that the structures and circuits shown are for the purpose of illustration only, and that various changes and modifications are to be considered as within the spirit of the present invention.

I claim as my invention:

1. A hot cathode device including an anode, a control electrode, and a cathode structure, said cathode structure including a porcelain body having a heater therein, a shield associated with the body, and a cathode element associated with the body, said shield being magnetically interposed between the heater and cathode element and out of electrical contact with the latter.

2. A hot cathode device including an

- anode, a cathode structure within the anode and out of contact therewith, said structure including a heat resistant rod having a heater element therein, a metallic sleeve surrounding the rod and having a heat resistant covering thereon, and a cathode element fitted over the rod and sleeve and insulated therefrom through said heat resistant covering. 20
- 5 3. A hot cathode device including an anode, a cathode structure within the anode and out of contact therewith, said structure including a heat resistant rod having a heater element therein, a metallic sleeve surrounding the rod and having a heat resistant covering thereon and having an external connecting wire attached thereto, and a cathode element fitted over the rod and sleeve and insulated therefrom through said 25 heat resistant covering. 30
- 10 15
- In testimony whereof I hereunto affix my signature.
- FREDERICK S. McCULLOUGH.
